T. T. BELL

AIR SUPPLY DEVICE FOR CARBURETORS

Filed July 20, 1922

INVENTOR.
Thomas T. Bell

By. *W. L. Fitzsimmons*
HIS ATTORNEY.

UNITED STATES PATENT OFFICE.

THOMAS T. BELL, OF PASADENA, CALIFORNIA.

AIR-SUPPLY DEVICE FOR CARBURETORS.

Application filed July 20, 1922. Serial No. 576,370.

To all whom it may concern:

Be it known that I, THOMAS T. BELL, a citizen of Canada, residing in the city of Pasadena, county of Los Angeles, and 5 State of California, have invented certain Improvements in Air-Supply Devices for Carburetors, of which the following is a specification.

The principal object of my device is to 10 provide a simple and economical device which can be readily affixed to the exhaust manifold and the carburetor of a gas engine for the purpose of supplying a mixture of warm and cool air to the carburetor, and for 15 causing its thorough mixture before it enters the carburetor.

I know it is old to provide a hood like device for conveying warm air from around the exhaust manifold to the carburetor. I 20 have provided in connection with such a device an intermediate extension or branch with a tapered inlet to said extension or branch for admitting cool or atmospheric air into said hood for mixture with the 25 warm air passing therethrough into the carburetor.

I have illustrated one practical embodiment of my invention on the accompanying sheet of drawings, which I will now 30 describe.

Figure 1 is a side elevation of the exhaust and intake manifolds, and carburetor of a motor, with my invention applied thereto;

Figure 2 is a side elevation of my device 35 detached;

Figure 3 is a sectional view of my invention, showing the inner construction and arrangement; and

Figure 4 is an edge view thereof.

Referring in detail to the drawings, 1 40 designates the usual exhaust manifold and 2, the usual intake manifold, and 3, the carburetor, of a gas engine.

My invention as here shown for illustrative purposes, comprises a hood-like portion, 4, adapted to fit around one side of the exhaust manifold, 1, as indicated, and having the stem, or tubular portion, 5, the lower end of which is connected to the carburetor, as shown.

Said hood-like portion 4 is provided with a forked attaching plate, 6, by means of

which it is held in place on the exhaust manifold 1, as illustrated in Fig. 1. In the tubular portion 5, of said device, I provide 55 a baffle plate, 7, as shown in Fig. 3, near which is a hole 8, over which is attached an extension or branch, 9, with which communicates a tapering member 10, having its outer or larger end open to the atmospheric 60 air, and its smaller end constituting a restricted inlet into said branch or extension, whereby the air is discharged or drawn into said branch through a nozzle like entrance, and expands as it enters the larger chamber 65 of the branch or extension member 9, from which it is drawn through the opening 8, and deflected by the baffle member 7, downwardly to mix with the warm air passing through the tubular portion 5 of the device 70 to the carburetor, 3, as will be clearly seen in the drawing.

In the form shown, I have provided a cover, 11, for the branch or extension member, and have mounted the tapering member 10 within a uniform tubular member, 12.

Thus as the warm air is drawn in under the hood-like member 4, and down through the tubular portion 5, to the carburetor, there is also drawn through the tapering member 10, into the branch or extension, 9, atmospheric air from around the engine, under the hood, which is discharged into the tubular member 5, mixed with the warm air, and fed to the carburetor for mixture 80 with the gasoline. Said hood-like member is also provided with a hole, 13, and with the spacing lugs, 14, whereby to provide air space between the hood and the exhaust manifold, and additional air inlet through 85 said hole 13, to said space.

I am aware that changes can be made in my invention as here illustrated without departing from the spirit of the same, and I do not, therefore, limit the invention to 90 the details shown, except as I may be limited by the hereto appended claim.

I claim:

In combination with the exhaust manifold and carburetor of a motor, an air supply device of the character shown and described comprising a hood-like device fitting around the exhaust manifold and connected to the carburetor, and a branch

connected to the tubular portion of said device and having a tapering air inlet thereinto, with the larger end outwardly and the smaller end inwardly of said branch, and a baffle member in said tubular portion of the device adjacent the place of connection of said branch, substantially as described.

Signed at Los Angeles, Los Angeles County, California, this 14th day of July, 1922.

THOMAS T. BELL.
